EX

D 19411

UNITED STATES PATENT OFFICE.

GILBERT L. CROWELL, JR., OF ARLINGTON, NEW JERSEY, ASSIGNOR TO
DOMINICK & HAFF, OF NEW YORK, N. Y.

DESIGN FOR A BACK FOR HAND-MIRRORS, &c.

SPECIFICATION forming part of Design No. 19,411, dated November 12, 1889.

Application filed September 21, 1889. Serial No. 324,682. Term of patent 7 years.

To all whom it may concern:

Be it known that I, GILBERT L. CROWELL, Jr., of Arlington, in the county of Hudson and State of New Jersey, have invented and produced a new and original Design for a Back for Hand-Mirrors or other Toilet Articles, of which the following is a specification.

My design is for the backs of hand-mirrors and similar-shaped articles.

10 The design is illustrated in the accompanying photograph, which represents a hand-mirror, but may be applied to any toilet article of similar shape.

The design consists in an ornamental border having the representation in relief of a flanged bead *a*, the continuity of which is broken at intervals by curved branches *c*, crossing the bead *a* and terminating in foliated scrolls *d*. At intervals in the representation of the flanged bead *a* and the branches *c*

with scrolls *d* is located a spreading leaf *e*, with a scalloped edge and spaced convex protuberances, and over the leaf *e* projects a branch with scrolls *d*. On either side of some of the leaves *e* extends, parallel with the bead *a*, a branch *f*, with flowers *g* and leaves *h*.

I claim—

The design for the back of a hand-mirror or other toilet article herein shown and described, the same comprising the back of said article, with the flanged bead *a*, branches *c*, with scrolls *d*, spreading leaf *e*, with spaced convex protuberances, branch *f*, leaves *g*, and flowers *h*, all arranged thereon, substantially as set forth.

GILBERT L. CROWELL, JR.
